UNITED STATES PATENT OFFICE.

HARVEY CLARK HURD, OF MONTEVISTA, COLORADO.

TRACE-CARRIER.

SPECIFICATION forming part of Letters Patent No. 746,839, dated December 15, 1903.

Application filed May 14, 1903. Serial No. 157,173. (No model.)

To all whom it may concern:

Be it known that I, HARVEY CLARK HURD, a citizen of the United States, residing at Montevista, in the county of Rio Grande and 5 State of Colorado, have invented a new and useful Trace-Carrier, of which the following is a specification.

This invention relates to trace-carriers, and has for its object to simplify and improve devices of this character and provide a device wherein the cockeyes of the traces will be prevented from accidental displacement, while at 10 the same time easily connected with and disconnected from the carrier when required; and the invention consists in certain novel 15 features of construction, as hereinafter shown and described, and specified in the claims.

In the drawings illustrative of the invention, in which corresponding parts are denoted 20 by like designating characters, Figure 1 is a perspective view of one of the improved devices complete. Fig. 2 is a longitudinal sectional elevation with the ends of the traces connected therewith.

25 The improved device comprises a skeleton frame formed with base members 10, preferably oblong in outline, and upwardly-arching members 11 12, spaced apart and connected centrally by a central member 13 and 30 provided with tongues 14 15, depending centrally from the arched members. The frame is likewise connected by intermediate transverse bars 16 17 and with transverse supporting members 18 19 near the ends of the base 35 members, as shown. All of these parts are preferably integral and of malleable iron or other suitable metal.

Connected as by rivets 20 21 centrally to the supporting members 18 19 are springs 22 40 23, the springs being held in recesses in the members 18 and 19, as shown. The springs 22 23 extend inwardly beneath the tongues 14 15 and upwardly beneath the bar 13, being formed with recesses at 28 29 in their free 45 ends embracing the bar and effectually preventing lateral displacement of the upper ends of springs while in use.

The cockeyes of the traces are indicated at 24 25 with sections of the traces connected 50 thereto, as shown at 26 27, and when applied the cockeyes will be inserted between the bars 11 and 16 and 12 and 17 and beneath the

tongues 14 15, respectively, depressing the springs by this action and being held in place by the return of the latter to their positions 55 in engagement with the bar 13, as shown. By this simple means the cockeyes and traces will be supported when not in use and all danger of displacement obviated, no matter how severe the concussions or jarring may be. 60

It frequently happens that harness after being taken from the horses is thrown about and subjected to severe jarring and concussion, and when this takes place the traces are very liable to be shaken loose from the 65 carriers as ordinarily constructed. With my improved arrangement, however, the springs 22 and 23 being firmly held at both ends from lateral displacement will not be affected by these movements and will retain the traces 70 in position during all the various positions in which the harness may be placed. Extending the springs to the bar 13 and "forking" their free ends, as at 28 29, whereby they are caused to embrace the sides of the 75 bar, is therefore an important feature of the invention, and, together with means whereby the lower ends of the springs are secured between the walls of the recesses in the members 18 19, adds materially to its value and 80 efficiency.

The device may be adapted to all the various sizes and forms of harness and may be attached thereto at any desired point, but will usually be attached at the intersection 85 of the back and hip straps in the ordinary manner.

The device may be plated, japanned, or otherwise ornamented or protected, as desired. 90

Having thus described the invention, what I claim is—

1. A trace-carrier comprising a skeleton frame having arching transverse brace-guards spaced apart and connected by a central longitudinal bar with spaced tongues depending from said brace-bars, transverse supports at the lower portion of said skeleton frame near its ends, and springs connected to said supports, and extending inwardly beneath said tongues and upwardly between the tongues and provided with recesses in their free ends in yieldable engagement with said longitudinally-disposed central bar, whereby the 100

cockeyes of the traces are adapted to be supported in yieldable engagement with the tongues and accidental displacement obviated and lateral displacement of the springs likewise prevented, substantially as described.

2. A trace-carrier comprising a skeleton frame having arched transverse brace-guards spaced apart and connected by a central longitudinal bar with spaced tongues depending from said brace-bars, transverse supports at the lower portion of said skeleton frame near its ends, and provided with transverse recesses to form seats and springs connected to said supports, within said seats, and extending inwardly beneath said tongues and then upwardly between the tongues and with re-

cesses in their free ends in yieldable engagement with said longitudinally-disposed central bar, whereby the cockeyes of the traces are adapted to be supported in yieldable engagement with the tongues and accidental displacement obviated and lateral displacement of the springs likewise prevented, substantially as described.

In testimony that I claim the foregoing as my own I have hereunto affixed my signature in the presence of two witnesses.

HARVEY CLARK HURD.
